UNITED STATES PATENT OFFICE.

WILLIAM WUERTHELE, OF PITTSBURGH, PENNSYLVANIA.

NOISE SUDUER AND PROTECTOR FOR BILLIARD-CUE BUTTS.

Application filed February 12, 1921. Serial No. 444,360.

To all whom it may concern:

Be it known that I, WILLIAM WUERTHELE, a citizen of the United States, residing at Pittsburgh, in the county of Allegheny and State of Pennsylvania, have invented certain new and useful Improvements in Noise Subduers and Protectors for Billiard-Cue Butts, of which the following is a specification.

This invention relates to a buffer device 10 designed to be attached to the butt end of a billiard cue and the like, primarily for the purpose of mitigating, as far as possible, the annoyance caused by the noise due to the prevalent habit of players of thumping the 15 butt end of their cues upon the floor between shots, and further to protect the butt end of the cue from injury due to such thumping action.

Further objects of the invention are to 20 provide a device of the character described, in a manner as hereinafter set forth, which may be attached to the butt end of a cue without the use of screws and the like, which is simple in its construction and arrangement, strong, durable and efficient in its use, 25 attractive in appearance, readily attached in position, and comparatively inexpensive to manufacture.

To the accomplishment of these and such 30 other objects as may hereinafter appear, the invention consists of the novel construction and arrangement herein specifically described, and illustrated in the accompanying drawing wherein is shown an embodiment 35 of the invention, but it is to be understood that the device shown is merely illustrative of what is now thought to be the best embodiment thereof, and that various changes in the form, proportion, and minor details 40 of construction may be resorted to, without departing from the principle or sacrificing any of the advantages of the invention, which come within the scope of the claims 45 hereunto appended.

In the drawing forming a portion of this specification and wherein like numerals of reference designate corresponding parts throughout the several views:

Figure 1 is a vertical elevation of a billiard cue provided at its butt with a buffer device in accordance with this invention, with a portion of the cue broken away.

Figure 2 is a similar view with the buffer

device and associated part of the cue butt shown in cross section. 55

Figure 3 is a vertical sectional view of the device.

Referring in detail to the drawing 1 denotes a substantially cup-shaped hollow body portion, preferably constructed from 60 resilient material, namely, rubber or its equivalent.

The body portion 1 is formed with the chamber 2 having a rounded bottom 3 which conforms to the contour of the butt end 4 65 of the cue 5 adapted to seat therein.

The upper end of the body portion 1 is formed with an inwardly disposed annular gripping flange 6 extending into the chamber 3. The flange 6 is substantially triangular in cross section and gradually increases in diameter toward the bottom 3 of the chamber 2.

A circular cushion disk 7 is formed integral with the outer face of the bottom of the 75 body portion 1 and is adapted to deaden the sound and noise if the cue is thumped upon the floor by the player, and further to prevent liability of marring or damaging the cue butt 4 by such thumping action. 80

My improved buffer device is attached to a billiard cue of the usual construction by reducing the diameter of the butt 4 sufficiently to permit of its insertion into the chamber 3 and to bring the periphery of the 85 body portion 1 flush with the periphery of the adjacent butt portion of the cue. An annular groove 8 is formed at the upper end of the reduced portion of the butt 4 for the reception of the annular gripping 90 flange 6.

A coating of glue, cement 9, or equivalent preparation is interposed between the reduced portion of the butt 4 and the wall of the chamber 3, thereby securely attaching 95 the device and preventing displacement thereof, without the use of screws and the like which are liable to split the butt of the cue. The flange 6 being triangular in cross section and the groove 8 being rectangular in cross section, only one-half of the latter will be filled by the former, leaving ample space for the entrance of glue, cement and the like, into the other one-half of the groove 8.

While illustrating and describing the application of my improved buffer device in

connection with a billiard cue, it will be understood that the same may be used for any purposes wherein it is found applicable.

What I claim is:—

- 5 1. A device for the purpose set forth comprising a chambered resilient body having an inwardly extending annular gripping flange flush with the top edge of said body.
- 10 2. A device for the purpose set forth comprising a chambered resilient body having an inwardly extending gripping flange at the top of the wall of the chamber in said body, said flange being flush with the top edge of said body.
- 15 3. A device for the purpose set forth comprising a chambered resilient body having the wall of the chamber provided with an inwardly extending gripping flange triangular in cross section, said flange having 20 wider portion flush with the top edge of said body.
- 25 4. A device for the purpose set forth comprising a hollow resilient cup shaped body open at its upper end and having a rounded closed bottom provided with a cushioning disk of less diameter than the diameter of the body, said body having its inner face provided with an inwardly extending annular flange flush with the top edge of the 30 body.
- 35 5. A device for the purpose set forth comprising a resilient body formed with a chamber having the upper portion of the wall thereof provided with an inwardly extending gripping flange flush with the top

edge of said body and a cushioning disk projecting from the lower face of the bottom of said body and of less diameter than the latter.

6. A device for the purpose set forth comprising an annular resilient body formed with a chamber having the upper portion of the wall thereof provided with an inwardly extending annular gripping flange of triangular contour in vertical section and a cushioning disk projecting from the lower face of said body and of less diameter than said body.

7. A device for the purpose set forth comprising an annular resilient body formed with a chamber having the upper portion thereof provided with an inwardly extending annular gripping flange substantially triangular in cross section, and flush with the top edge of said body, said chamber having a rounded bottom, and a protuberance extending from the outer face of the bottom of said body and in the form of a circular disk and of less diameter than said body.

8. A device for the purpose set forth comprising a hollow cup shaped resilient body having an open top and a closed bottom, said body formed with an outwardly projecting cushioning disk, and said body having its inner face formed with an inwardly projecting annular gripping flange flush with the top edge of said body.

In testimony whereof I affix my signature.

WILLIAM WUERTHELE.
